UNITED STATES PATENT OFFICE.

WILLIAM P. KIEST, OF NEWDALE, IDAHO.

TRACE-CARRIER.

1,253,838.

Specification of Letters Patent. Patented Jan. 15, 1918.

Application filed November 22, 1916. Serial No. 132,886.

To all whom it may concern:

Be it known that I, WILLIAM P. KIEST, a citizen of the United States, residing at Newdale, in the county of Fremont, State 5 of Idaho, have invented certain new and useful Improvements in Trace-Carriers; and I do hereby declare the following to be a full, clear, an exact description of the invention, such as will enable others skilled in the 10 art to which it appertains to make and use the same.

This invention relates to harness fittings, and has particular reference to trace carriers.

15 The object of the invention is to provide an improved form of those harness fittings which combine a connecting plate or device for the back strap, crupper strap and hip straps, and a supporting device for the ends 20 of the tugs or traces. In this connection the invention contemplates a simply constructed device which may be readily employed in a harness structure either as a plain connection or as a part of a back pad to which the 25 device is sewed, or in which it is embedded. To this end, the device consists, generally speaking, of a continuous heavy wire or bar in which are formed certain bends and turns and from which results the completed structure. 30 This construction provides a very light fitting without sacrificing any of the necessary strength which it must possess. By making the devices of wrought wire or 35 bar metal, an added strength may be given to it which the ordinary cast fitting which is known to me does not have.

With the above objects in view and such other objects as may hereinafter appear, my invention will now be fully set forth and described, reference being had to the accompanying drawings.

In the drawings:—

Figure 1 is a perspective view of the device showing the ends of the harness straps 40 connected thereto, and

Fig. 2 is a side elevation of the device and of a trace cockeye in engaging relation therewith.

Fig. 3 is a section on line 3—3 of Fig. 1.

50 Referring more particularly to the drawings, the device is shown to be a suitably rectangular base member from whose longitudinal sides a pair of locking loops rise, the loops being shaped so that the eye portion 55 of a cock-eye may be inserted from certain angles, and be prevented from coming out

when standing at any normal angle. The rectangular base frame and the vertically standing locking or retaining loops are formed from a continuous heavy wire bar. 60 The vertical loop 2 is formed from one end of the continuous blank length and below the loop is turned back to form one side of the base 1, the bight of the blank being passed through a loop 3 formed upon the first end of the length at one side of the loop 2. From the end of the longitudinal side of the rectangular base 1 the blank is turned at right angles to form the short side 4 and again at right angles to parallel the first 70 longitudinal side and to form the base of the second retaining loop 5. After forming the base of the loop 5, the blank is turned upwardly and shaped into the latter, and is then wrapped as at 6 around the second longitudinal side of the base. From the wraps 75 6 the blank is laid along the longitudinal side of the frame 1 which forms the base of the loop 5 and is continued therebeyond a proper distance to provide a strap hold, the 80 blank from the forward end of this continuation being turned at right angles to form the second transverse side 7 of the frame 1, and the second end of the frame being then turned inwardly and wrapped at 8 around 85 the corner of the first loop 2. In this manner the complete device is formed from a single length of material.

After the device has been formed as above described, the side 4 becomes the point of 90 attachment for a back strap 9, the longitudinal sides of the frame 1, adjacent the side 4 become the points of attachment for the hip straps 10, while the second short or transverse side 7 becomes the point of attachment 95 for the crupper strap 11.

The retaining loops 2 and 5 are formed with the lower elongated openings 12 and the vertical narrow openings 13 surmounting the openings 12 so that a pair of opposing angular projections 14 are provided between the horizontal and vertical portions of the loops. The vertical dimension and the widest transverse dimension are too narrow for the passage of a cock-eye at the rear 105 end of the trace, but by tipping the cock-eye in one direction, and passing the eyelet thereof around the projections upon the opposite ends of the loops the eyelet may be readily slipped into the loop, but when the 110 cock-eye has been turned into flat relation and allowed to drop against the vertical

sides of the horizontal part of the loop it is practically impossible for the cock-eye to fall out of the loop without an agency which will lift it into the diagonal position which it was given when inserted in the loop. In order to prevent the reins from catching in between the loops 2 and 5, a transverse cross or brace bar 15 may be used to join the upper ends of the loops, the ends of the brace bar being turned around the material of the loops and serving also to hold them in rigid relation.

From the foregoing it will be obvious that I have provided a very simple and improved form of trace carrier, one in which the trace ends may be located without extra effort, and in which when the traces have been placed in position, there is little danger of the ends working loose and falling. Forming the device in one continuous length, it is possible to manufacture economically a device which has heretofore been made in cast metal, and has therefore not had the capa-

bilities or strength of a wrought metal structure.

25

What I claim as my invention is:—

A trace carrier comprising a single piece of wire so bent as to form a rectangular base frame adapted to receive the ends of a back strap, of hip straps, and of a crupper strap, 30 and a pair of loops rising vertically from the rectangular base frame and each consisting of a lower section and an upper section, the said upper section being less in width than the lower section, thus providing oppositely 35 projecting angular shoulders over either of which the eye portion of a cockeye is passed in engaging the latter with one of the loops, substantially as described.

In testimony whereof, I affix my signature, in the presence of two witnesses.

WILLIAM P. KIEST.
